US00D807793S

(12) **United States Design Patent** (10) **Patent No.:** **US D807,793 S**
(45) **Date of Patent:** **** Jan. 16, 2018**

(54) **ROLLATOR**

(71) Applicant: **Medline Industries Inc.**, Northfield, IL (US)

(72) Inventors: **Michael Paterson**, Chicago, IL (US); **Tong Jin Kim**, West Lafayette, IN (US); **Kegan McDaniel**, Chicago, IL (US); **Luke Westra**, Chicago, IL (US)

(73) Assignee: **Medline Industries, Inc.**, Northfield, IL (US)

(**) Term: **14 Years**

(21) Appl. No.: **29/523,431**

(22) Filed: **Apr. 9, 2015**

(51) LOC (11) Cl. **12-12**

(52) U.S. Cl.

USPC **D12/130**

(57) **CLAIM**

We claim the ornamental design for a rollator, as shown and described.

DESCRIPTION

FIG. 1 is a top perspective view of a rollator showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view thereof, the seat shown in an alternate position;

FIG. 10 is a bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a top perspective view thereof, in a folded position;

FIG. 18 is a bottom perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof; and,

FIG. 24 is a bottom plan view thereof.

1 Claim, 22 Drawing Sheets
